AMUSEMENT RIDE CAR

Karl W. Bacon, Mountain View, and Edgar O. Morgan,
Palo Alto, Calif., assignors to Disneyland, Inc., Anaheim, Calif., a corporation of California

Filed Apr. 4, 1960, Ser. No. 60,038

Term of patent 14 years

(Cl. D34—15)

We claim:

The ornamental design for an amusement ride car substantially as shown.
